DRIVING DEVICE FOR TEXTILE MACHINES

Kurt Gustav Scheibel, Dresden-Strehlen, Germany, assignor to Würker G. m. b. H., Dresden A, Germany

Application October 23, 1934, Serial No. 749,641
In Germany October 6, 1933

14 Claims. (Cl. 66—82)

This invention relates to a driving device for textile machines. It is well known that in such machines including their different sub-groups as, for instance, knitting machines many parts have to be moved in very different manners so as to obtain the regular formation of the meshes and the forward movements of the ware produced. Frequently the said parts must be stopped for regular cooperation, whereas other parts even then must be set into more or less rapid motion. It is important to remark here that in this case a great number of needles must be moved by means of the relatively heavy needle bars in various manners.

It is common to use a cam-control for moving the several parts of such machines and it has also been proposed to obtain a compulsory guidance by means of continuous curves. However cam-guiding only permits of relatively small working speeds as a close contact between the cam pins and the cams cannot be attained even when using strong springs, and pins guided in continuous curves are worn out so rapidly that an exact guidance becomes illusory. This inconvenience cannot be removed by substituting for the continuous curve the well-known arrangement of two eccentrics moving in opposite directions, by which at most the knocking effect is reduced without reducing the wear, and no exact guidance in high-speed machines is obtained.

Where it has been attempted to employ combined gears in textile machines instead of the usual pure eccentric-drive, always open or continuous cam-guiding was combined with swing-lever guiding whereby obviously no increase of the working-speed can be obtained, but only drives of still more complicated construction are produced which, it is true, make it possible to create special possibilities of driving, but at the expense of the working-speed.

In contradistinction hereto the parts of the textile machine to be moved are actuated from the couple-bar of a quadrangular link system containing a crank by a connecting-rod linked to the couple. It is well known that the individual points of the couple-bar of a quadrangular link system containing a crank or arms or the like mounted on the couple-bar describe continuous curves having in parts the shape or approximately the shape of circular arcs, and that the connecting-rod linked to the couple-bar may be proportioned as to its length and to the position of its point of application in such a manner that this point—which is in itself capable of be-

ing displaced—stands still while the linkage point describes a circular arc of the couple-curve. In this way it is possible by correctly choosing the couple-curve to insert one or several stops at any desired time except at the reversal points of the connecting crank. On the other hand, a movement absolutely insensible to the actions of high speed takes place of parts coupled with one another only by joints, which at will may be made strong and resistive as to journalling and so forth. In this way with a relatively small motion of masses a clean guide of the gear elements allowing any speed is obtained.

It may be noted that it has already been proposed to effect the control of the movable elements of textile machines by a connecting-rod linked to a swing-arm, the bolt of the joint being radially adjustable and being guided in a curve whilst the swing-arm itself forms part of a quadrangular link system containing a crank. In this construction the fulcrum is not guided in a continuous circular curve, but still in a guiding curve in which it moves to and fro, whereby it is again impossible, especially with higher working-speeds, to avoid the wear in the curve, without counting that in the old construction the connecting-rod does not derive its motion from the couple-bar of the quadrangular link system containing a crank and therefore the benefits of the stopping at any desired point or points during one working revolution cannot be obtained.

The derivation from the couple-bar of the quadrangular link system containing a crank does not exclude connecting a plurality of driving rods with one and the same couple-bar so that if desired all movable elements of a textile machine coming into consideration may be driven by means of a single quadrangular link system containing a crank, with high speed and with independent stops.

It may further be noted that it is old in itself to derive the drive of the movable elements of machines from the couple-bar of a quadrangular link system containing a crank, but that just the application of this measure to textile machines entails the above-mentioned especial advantages.

The invention is illustrated by way of example in view of a cotton-machine in the annexed drawing which shows diagrammatically the arrangement of the intermediate members for moving a needle-bar in vertical and horizontal direction.

The needles 1 are fixed in the well-known manner on a needle-bar 2 made of a light metal for reducing the weight. The needle-bar 2 is

fulcrumed in a joint 3 and has a prolonged arm 4. The needle-bar is supported by two levers 5 journalled on a shaft 6 supported by the arms 16. The levers 5 are divided in the middle by 5 a slot 7 to permit of adjusting the needle-bar as to its height by screws 8. The movement of the single needle-bars which are arranged one beside the other is effected from a lever 9. The levers 9 are likewise journalled on the shaft 6, 10 but are connected with the levers 5 supporting the needle-bars. Each lever 9 is connected with a link 10 by a joint 11 and is driven by a quadrangular link system. The latter comprises an eccentric 12 mounted on a main-shaft 13. This 15 eccentric forms the crank of the quadrangular link system and encompasses, by extension of the pivot, the driving shaft. Owing to the large surface, heavy forces may be sustained, an important advantage in the case of high speeds of 20 the machine.

On the eccentric 12 is mounted the couple-bar 14 which is engaged by the wing 17 by means of the pivot 15. The wing 17 is fulcrumed at 16' in the frame 16 of the machine. The couple-bar 25 is engaged by the link 10 by means of the pivot 18. The axis of the pivot 18 forms one couple-point which on the rotation of the eccentric 12 describes a curved path which may greatly vary according to the disposition of the couple-point 30 in view of the quadrangular link system and is correspondingly subjected to different rules.

According to the selection of a couple-point the movement of the link 10 may be transferred to the lever 9 with different strokes, but also the 35 times and speeds may be varied. Moreover certain requirements demanded by the member to be driven may be fulfilled by these couple-curves. For instance, when the vertical movement of the needle is to be stopped at a certain time and in 40 a predetermined position, a couple-point may be selected in which fraction of a couple-curve corresponds to or approximates the radius of the link. As soon as the link swings out according to the radius of the couple-curve, the lever 9 45 is stopped. Then the bolt of the joint forms a fulcrum for the link 10.

Couple-points may also be selected, the motion-curve of which comprises at several points a circular arc having the same radius. In this case, 50 when employing a link of corresponding length, a number of stops may be obtained during one revolution of the crank of the quadrangular link system corresponding to the number of curve elements having a corresponding circular arc 55 curvature.

It is also forthwith possible to derive one or more movements from the couple-bar of a quadrangular link system. In the form shown, for instance, the horizontal movement of the needle 60 is derived too. In the bearing 19 on the couple-bar a bolt 20 is journalled carrying an eccentric 21 and possessing a lever 22 at its foremost point. The lever is drawn by a draw-spring 23 against a stop pin 24. This stop pin 24 is attached to 65 a link 25 consisting of two parts connected with each other by screws 26. The other end of the link is connected with the lever 4 by a joint 27. The link 25 is divided into two parts in order 70 that an easier adjustment when mounting may be obtained. However the links may also be differently adjusted by providing a set-screw or the like between the two parts of the link. On the link 25 a second stop pin 28 is provided serving likewise as an abutment for the lever 22.

When in a certain case the needle 1 is to be brought out of the range of its working position, the lever 22 is swung from the left to the right hand (Fig. 1) and touches the stop pin 28, the draw-spring tending to press the lever against 5 the stop pin 28. During this motion the eccentric 21 has been swung out and draws the link 25 likewise to the right. The lever 4 follows this movement again swinging the needle-bar with the needles to the left. This arrangement affords the advantage of the whole of the moving members not being separated from one another, as hitherto usual, so that even with a rapid speed of the machine an automatic disconnection of the lever 22 is excluded. Of course 10 also several bolts 20 may be connected with one another whereby several needle-bars are disconnected at the same time. Also the link 25 may fulfil the same requirements as described in connection with the link 10. Also here it is possible to obtain different speeds and movements 15 as well as stops.

The here described drive is not only distinguished by its stability and simplicity as compared with the drives heretofore known, but is 20 extraordinarily suitable for allowing high revolution members. As large surfaces are provided for the bearings a quiet movement of the machine is warranted.

Finally it may be noticed that of course couple-curves may also be derived from couple-gears in which a straight guiding is substituted for a link. 30

In the following claims the term "connecting bar" is intended to define a couple bar described 35 above.

I claim:

1. A driving means for the mesh forming elements of textile machines such as needle bars, taking off combs or the like comprising a drive 40 shaft, a crank actuated by said drive shaft, a connecting bar pivotally connected to said crank, a link oppositely connected to said connecting bar and having at the other end a fixed fulcrum, a connecting rod pivotally connected to 45 said connecting bar, said connecting rod being adjustable in length and means connecting said connecting rod to said elements.

2. A driving means for the mesh forming elements of textile machines such as needle bars, taking off combs or the like comprising a drive 50 shaft, a crank actuated by said drive shaft, a connecting bar pivotally connected to said crank, a link having one end pivotally connected to said connecting bar and the other end pivotally connected to a fixed fulcrum, a plurality of adjustable connecting rods adjustable in length pivotally connected to said connecting bar and means connecting said connecting rods to said elements. 55

3. A driving means for the mesh forming elements of textile machines such as needle bars, taking off combs or the like comprising a drive 60 shaft, a link system actuated by said drive shaft including a connecting bar, an eccentric mounted in said connecting bar and means controlled by 65 said eccentric governing the horizontal movements of said elements.

4. A driving means for the mesh forming elements of textile machines such as needle bars, taking off combs or the like comprising a drive 70 shaft, an eccentric mounted upon said drive shaft, a connecting bar actuated by said eccentric, a link having one end pivoted to said connecting bar and the other end pivoted to a fixed fulcrum, a 75

connecting rod connected to said connecting bar governing the vertical movements of said elements, a second eccentric mounted upon said connecting bar and means governing the horizontal movements of said elements controlled by said eccentric.

5. A driving means for the mesh forming elements of textile machines such as needle bars, taking off combs or the like comprising a drive shaft, a link system actuated by said drive shaft, including a connecting bar, means connecting said elements to said connecting bar of said link system, an eccentric mounted upon said connecting bar, means governed by said eccentric controlling the horizontal movements of said elements, a lever member upon said eccentric and means for holding said lever member in two different positions so as to maintain said elements in either operative or inoperative position.

10. 6. A driving means for the mesh forming elements of textile machines such as needle bars, taking off combs or the like comprising driving means, a connecting bar actuated by said driving means and means connecting said elements to said connecting bar at pivot points on said bar and offset from the line of action of said connecting bar whereby standstills and positive and negative accelerations of said elements may be secured.

15. 7. A driving means for the mesh forming elements of textile machines such as needle bars, taking off combs or the like comprising a drive shaft, a crank driven by said drive shaft, said crank constituting one member of a link system, a connecting bar actuated by said crank and means connecting said elements to said connecting bar at pivot points on said bar and offset from the line of action of said connecting bar whereby standstills and positive and negative accelerations of said elements may be secured.

20. 8. A driving means for the mesh forming elements of textile machines such as needle bars, taking off combs or the like comprising a drive shaft, a crank driven by said drive shaft, a connecting bar connected to said crank, a link member connected to said connecting bar and having a fixed fulcrum and means connecting said elements to said connecting bar at pivot points offset from the line of action of said connecting bar whereby standstills and positive and negative accelerations of said elements may be secured.

25. 9. A driving means for the mesh forming elements of textile machines such as needle bars, taking off combs or the like comprising a drive shaft, a crank actuated by said drive shaft, a connecting bar pivotally connected to said crank, a link connected at one end to said connecting bar, said link having its other end pivoted to a fixed fulcrum, a connecting rod pivotally connected to said connecting bar and a pivot point offset from the line of action of said connecting bar and said

elements being actuated by said connecting rod whereby standstills and positive and negative accelerations of said elements may be secured.

10. A driving means for the mesh forming elements of textile machines such as needle bars, taking off combs or the like comprising a drive shaft, a link system having a connecting bar actuated by said drive shaft, a plurality of connecting rods connected to said connecting bar at pivot points offset from the line of action of said connecting bar and means connected to said connecting rods for actuating said elements whereby standstills and positive and negative accelerations of said elements may be secured.

15. 11. A driving means for the mesh forming elements of textile machines such as needle bars, taking off combs or the like comprising a drive shaft, an eccentric mounted upon said drive shaft, a connecting bar pivotally mounted upon said eccentric, a link pivoted at one end to said connecting bar and having the other end pivoted at a fixed fulcrum and means connecting said elements to said connecting bar at pivot points offset from the line of action of said connecting bar whereby standstills and positive and negative accelerations of said elements may be secured.

20. 12. A driving means for the mesh forming elements of textile machines such as needle bars, taking off combs or the like comprising driving means, a link system having a connecting bar actuated by said driving means and a connecting rod pivoted to said connecting bar at a point offset from the line of action of said connecting bar connecting said elements whereby standstills and positive and negative accelerations of said elements may be secured.

25. 13. A driving means for the mesh forming elements of textile machines such as needle bars, taking off combs or the like comprising driving means, an eccentric actuated by said driving means, a connecting bar controlled by said eccentric and means connecting said elements to said connecting bar at pivot points on said bar and offset from the line of action of said connecting bar whereby standstills and positive and negative accelerations of said elements may be secured.

30. 14. A driving means for the mesh forming elements of textile machines such as needle bars, taking off combs or the like comprising driving means, a link system having a connecting bar actuated by said driving means, links connected to said connecting bar at pivot points offset from the line of action of said connecting bar, said links corresponding to the radii of arcs contained in the curves defined by fixed points in said connecting bar and being connected to said elements whereby standstills and positive and negative accelerations of said elements may be secured.
